UNITED STATES PATENT OFFICE.

GUSTAV TER MEER, OF HANOVER-LINDEN, GERMANY.

OVERFLOW MANIFOLD FOR CENTRIFUGAL SEPARATORS.

Application filed March 11, 1925. Serial No. 14,678.

To all whom it may concern:

Be it known that I, GUSTAV TER MEER, a citizen of Germany, and resident of Hanover-Linden, Germany, have invented certain new and useful Improvements in Overflow Manifolds for Centrifugal Separators, of which the following is a specification.

This invention is an improvement in that type of centrifugal separator in which there is an imperforate peripheral wall or drum and an outlet for the effluent liquid spaced inwardly therefrom. Such separators may be designed for continuous or batch operation, and may discharge the solid or separated material in any suitable manner. A construction of this general type is shown in my prior Patent 1,160,635, issued November 16th, 1915. In the construction there shown the effluent liquids are discharged through a central opening in the cover and over an annular overflow edge.

Within the chamber of such a separator the solids separated from the liquid collect against the inner surface of the drum with their inner surface substantially in the form of a parabola, while the inner surface of the liquid which is nearer to the center of the drum is substantially cylindrical. The clearest liquid is that nearest to such inner surface, but this often contains considerable quantities of solid matter which is of lighter specific gravity than the liquid, or which tends to float therein. Therefore it has been considered desirable to place the overflow as near as possible toward the center of the chamber, but even this does not give a pure liquid.

The separation of the solid particles from the liquid by centrifugal force is disturbed in the inner part of the chamber by the current of incoming liquid so that some small particles of slightly greater specific gravity than the liquid are kept in the liquid by this disturbing action and pass out along the overflow. It is obvious that the nearer the overflow edge is to the center or axis, the shorter is the circumferential length of such edge, and the deeper will be the layer of liquid passing over the overflow edge. Furthermore the less effective will be the action of centrifugal force. Thus a larger amount of solid particles will pass out with the effluent liquid.

The object of the present invention is to increase the relative diameter of the overflow edge and to increase the length of such

edge, whereby the rate of current flow over the edge is decreased and smaller solid particles are less subject to such current and more influenced by centrifugal force. Thus more complete separating action is secured and the overflowing liquid is clearer than has heretofore been possible in this type of apparatus.

If merely the diameter of the overflow be enlarged this correspondingly decreases the volume or holding capacity of the chamber and is not in itself satisfactory. Therefore as an important feature of my invention I provide a plurality of overflow edges arranged in superposed relationship within the separation chamber, and disposed along approximately the inner substantially cylindrical surface of the body of liquid therein. Such overflows may for example consist of simple tubes which lead outwardly from the upper portion of the inner cylindrical liquid surface and operate to drain off liquid overflowing into the open inner ends of such pipes. The liquid would be delivered through such pipes by the action of centrifugal force. The liquid may overflow not only from the upper portion of the inner cylindrical liquid surface but also from the center portion of such surface. The openings may face toward the outer peripheral wall or toward the center, but the pipes leading therefrom should be so disposed that the action of centrifugal force conducts liquid from said openings to the exterior of the apparatus.

Instead of single pipes, annular horizontal rings may be incorporated in the separator and in axially spaced relationship with annular slits upon the inner or outer surfaces, the edges of which slits serve as overflow edges. Such annular rings would constitute enlarged inlet openings for pipes leading to the exterior of the separator. The annular rings are so spaced that liquid may pass through between them, this being particularly essential if the slits or annular openings in said rings face inwardly rather than outwardly.

Various different constructions may be designed within the scope of my invention, and it is therefore obvious that the specific form illustrated in the accompanying drawings is to be considered in an illustrative rather than in a limiting sense.

In these drawings:

Fig. 1 is a central longitudinal section

showing the positions which the solid and liquid assume in operation, and

Fig. 2 is a transverse section on the line 2—2 of Fig. 1.

- 5 In the construction illustrated the bottom or floor 1 and the cover or top 2 are connected together, and the cover is of annular form with an annular overflow edge 3. The outer peripheral wall 4 is imperforate and 10 may be moved endwise in respect to the top and bottom to facilitate the discharge of the solid material as in the construction shown in my prior patent above referred to.

In the construction illustrated I carry out 15 my present invention by providing a plurality of annular vertically spaced rings 5 which are superposed within the separator and with inwardly facing annular openings or slits. The rings are shown as of channel 20 shape in cross section, whereby two annular overflow edges are presented at the opposite sides of the slit. These overflow edges face inwardly and are in a cylindrical surface which approximately coincides with the 25 cylindrical inner liquid surface. They are of approximately the same diameter as the overflow edge 3. The several rings or channels are connected together by a plurality of vertically disposed outlet pipes 6, and the 30 upper ring or channel is connected by similar pipes to outlets 7 through the top wall or cover of the separator. These outlets 7 are arranged in a circle of slightly greater diameter than the overflow edge 3.

35 In operation the mixture to be separated is delivered to the chamber and the action of centrifugal force causes the solid matter A to assume a position against the outer wall 4, and with its inner surface substantially in the form of a parabola. The liquid B forms a layer within the solid matter and when the cylindrical inner surface of this liquid reaches the grooves 5, it overflows the edges thereof and is delivered from the separator through the pipes 6 and 7. It will be obvious that the overflow of liquid takes 45 place not only at the normal overflow 3, but also at both of the annular overflow edges of each of the grooves. As the liquid 50 flows to these overflow edges from the top and bottom, as shown by the arrows, the result is that even when only a single ring or channel is used it affords a length of overflow edge double that of the edge 3. By 55 using a plurality of grooves the length of overflow edge is correspondingly multiplied. As the overflow liquid is thus distributed

over a very greatly increased overflow surface the liquid with a uniform inflow of sludge will pass over the overflow edges at 60 decreased speed and in decreased depth, and with correspondingly decreased capacity for carrying out solid particles.

Having thus described my invention, what I claim as new and desire to secure by Letters Patent is:

1. A centrifugal separator having an imperforate peripheral wall, a plurality of annular outlets spaced inwardly from said wall at equal distances from the axis of rotation and at axially spaced points, and means for conducting liquid from each of said outlets and entirely disposed at a greater distance from the axis of rotation than are any of said outlets. 70

2. A centrifugal separator having an imperforate peripheral wall, a cover having an annular overflow edge, and a plurality of auxiliary overflow edges of annular form spaced at equal distances from the axis of rotation and below said cover, and conduits entirely disposed outward radially beyond said first mentioned overflow edge for conducting liquid from said auxiliary overflow edges. 80

3. A centrifugal separator having a separator chamber and a plurality of superposed spaced annular members within said chamber, each having a pair of annular overflow edges and outlet pipes connected to 90 said members.

4. An overflow mechanism for centrifugal separator chambers, including a plurality of annular axially spaced inwardly facing channels having outlet pipes connected 95 thereto and serving to support the same.

5. A centrifugal separator having an imperforate peripheral wall, a plurality of annular inwardly facing channels spaced inwardly from said wall at equal distances 100 from the axis of rotation and at axially spaced points, the flanges of said channels presenting overflow edges for the delivery of liquid from the separator into said channels, and outlet conduits leading from said 105 channels.

Signed at Bremen, in the free State of Bremen, and Republic of Germany, this 19th day of January, A. D. 1925.

DR. GUSTAV TER MEER.
